(57) **CLAIM**

The ornamental design for an optical disk for recording information, as shown and described.

DESCRIPTION

FIG. 1 is a front view of an optical disk for recording information showing my new design;

FIG. 2 is a rear view thereof; and,

FIG. 3 is a side elevational view thereof, it being understood that the side view is the same about the entire circumference of the disk.

The annular surface portions in FIG. 2 between the annular transparent portions are mirror-like reflective surfaces.
